UNITED STATES PATENT OFFICE

151,618

DESIGN FOR AN ATOMIZER SPRAY ATTACHMENT FOR A CONTAINER

Samuel Gimelli, Bern, Switzerland, assignor to
Drugs Limited, London N., England

Application December 9, 1946, Serial No. 135,349
In Great Britain June 12, 1946

Term of patent 14 years

(Cl. D83—1)

To all whom it may concern:

Be it known that I, Samuel Gimelli, a Swiss citizen, residing at Beaulieustr 6, Bern, Switzerland, have invented a new, original, and ornamental Design for an Atomizer Spray Attachment for a Container, of which the following is a specification, reference being had to the accompanying drawing, forming part thereof.

Fig. 1 is a front elevational view of an atomizer spray attachment for a container showing my new design;

Fig. 2 is a side elevation thereof;

Fig. 3 is a rear elevation thereof;

Fig. 4 is a top plan view, and

Fig. 5 is a bottom plan view thereof.

I claim:

The ornamental design for an atomizer spray attachment for a container, as shown.

SAMUEL GIMELLI.
